(57) **CLAIM**

The ornamental design for a ceiling-mount camera, as shown and described.

DESCRIPTION

FIG. 1 is a rear-right perspective view of a ceiling-mount camera according to a first embodiment of the claimed design.

FIG. 2 is a front-left perspective view of the ceiling-mount camera of FIG. 1.

FIG. 3 is a front view of the ceiling-mount camera of FIG. 1.

FIG. 4 is a rear view of the ceiling-mount camera of FIG. 1.

FIG. 5 is a left side view of the ceiling-mount camera of FIG. 1.

FIG. 6 is a right side view of the ceiling-mount camera of FIG. 1.

FIG. 7 is a bottom view of the ceiling-mount camera of FIG. 1.

FIG. 8 is a top view of the ceiling-mount camera of FIG. 1.

FIG. 9 is a rear-right perspective view of a ceiling-mount camera according to a second embodiment of the claimed design.

FIG. 10 is a front-left perspective view of the ceiling-mount camera of FIG. 9.

FIG. 11 is a front view of the ceiling-mount camera of FIG. 9.

FIG. 12 is a rear view of the ceiling-mount camera of FIG. 9.

FIG. 13 is a left side view of the ceiling-mount camera of FIG. 9.

FIG. 14 is a right side view of the ceiling-mount camera of FIG. 9.

FIG. 15 is a bottom view of the ceiling-mount camera of FIG. 9; and,

FIG. 16 is a top view of the ceiling-mount camera of FIG. 9.

The broken lines in the drawings illustrate portions of the ceiling-mount camera that form no part of the claimed design. Interior portions of the ceiling-mount camera as viewed through the vent openings at the top and bottom of the ceiling-mount camera and as illustrated in broken lines in FIGS. 7 and 15 form no part of the claimed design.

The stipple shading in FIGS. 9-16 represents contrast in appearance, but any pattern formed by the stipple shading forms no part of the claimed design and no particular color is claimed.
